(Cl. D85—2)

To all whom it may concern:

Be it known that I, Vernon D. Griffith, a citizen of the United States, residing at Omaha, in the county of Douglas and State of Nebraska, have invented a new, original, and ornamental Design for a Combination Cigarette Pack and Coin Container, of which the following is a specification, reference being had to the accompanying drawings, forming part hereof.

In the drawings:

Fig. 1 is a perspective view of a combination cigarette pack and coin container, showing my new design;

Figs. 2 and 4 are respectively front and rear elevational views;

Fig. 3 is a side elevational view; and

Fig. 5 is a top plan view thereof.

I claim:

The ornamental design for a combination cigarette pack and coin container, as shown.

VERNON D. GRIFFITH.
